US00D879810S

(12) **United States Design Patent** (10) **Patent No.:** **US D879,810 S**
Boltz et al. (45) **Date of Patent:** **** Mar. 31, 2020**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Sebastian Boltz**, Elmshorn (DE);
Thorsten Quandt, Hamburg (DE);
Melanie Siemers, Hamburg (DE)

(73) Assignee: **Apple Inc.**, Cupertino, CA (US)

(**) Term: **15 Years**

(21) Appl. No.: **29/622,292**

(22) Filed: **Oct. 16, 2017**

Related U.S. Application Data

(63) Continuation of application No. 29/515,146, filed on Jan. 20, 2015, now Pat. No. Des. 803,880.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the office upon request and payment of the necessary fee.

The sole FIGURE shows a display screen or portion thereof with graphical user interface showing our new design.

The peripheral dashed broken line illustrates a display screen or portion thereof, and forms no part of the claimed design.
